UNITED STATES PATENT OFFICE.

THOMAS H. WATSON, OF NEW YORK, N. Y.

IMPROVEMENT IN HYDRAULIC JACKS.

Specification forming part of Letters Patent No. 44,358, dated September 20, 1864.

To all whom it may concern:

Be it known that I, THOMAS H. WATSON, of the city, county, and State of New York, have invented an Improved Hydraulic Jack; and I do hereby declare that the following is a full and exact description thereof, reference being had to the accompanying drawings, and to the letters of reference marked thereon.

Figure 1 is a sectional elevation of hydraulic jack, as patented under No. 8,203. Fig. 2 is a plan view of same. Fig. 3 is a sectional elevation of improved hydraulic jack. Fig. 4 is a plan view of same.

The nature of my invention consists in providing a reservoir holding fluids sufficient, when forced into the cylinder of the jack, to push the ram out its entire length when it is in a horizontal position, which is not accomplished by the hydraulic jacks now in use and described in Fig. 1, in which the force-pump is in the center of the reservoir, and when the jack is in a horizontal position half the contents of the reservoir is below the center of

the pump and cannot run into and supply it with water sufficient to more than one-third fill the cylinder; consequently the ram is forced out only one-third of the distance required. The fluid-reservoir on the upper or front side of the head, as drawn in Fig. 3, A, together with the ram B, containing sufficient water to fill the cylinder when in a horizontal position, thereby forcing out the ram the required distance.

I do not claim the invention of a portable hydraulic jack as patented under No. 8,203, and described in Fig. 1; but

What I claim, and desire to secure by Letters Patent, is—

The fluid reservoir on the upper or front side of the head when in a horizontal position, as described, and for the purposes set forth.

THOMAS H. WATSON.
